UNITED STATES PATENT OFFICE.

JOHANNES P. ULDERUP, OF NEW YORK, N. Y.

ACTUATING AND REVERSING MECHANISM FOR PUMPS.

1,275,800.

Specification of Letters Patent. Patented Aug. 13, 1918.

Application filed April 27, 1917. Serial No. 164,912.

To all whom it may concern:

Be it known that I, JOHANNES P. ULDERUP, a subject of the German Emperor, and a resident of the city of New York, Jamaica, 5 borough of Queens, in the county of Queens and State of New York, have invented a new and Improved Actuating and Reversing Mechanism for Pumps, of which the following is a full, clear, and exact description.

10 The invention relates to internal combustion engines using liquid fuel for the motive agent, and its object is to provide a new and improved actuating and reversing mechanism for the pump to insure an accurate 15 functioning of the pump for the latter to deliver liquid fuel to the working chamber of the engine, and arranged to permit convenient reversing of the engine whenever it is desired to do so. Another object is to use 20 the actuating and reversing mechanism for maintaining a uniform speed of the engine.

In order to accomplish the desired result, use is made of a main feed pump adapted to supply an engine cylinder with fuel to periodically effect the explosions during normal 25 running of the engine, a reversing pump adapted to supply the said engine cylinder with fuel to effect an explosion for reversing the engine, independent actuating mechanisms driven from rotatable parts of the 30 engine, one for actuating the said main feed pump and the other the said reversing pump, and connecting mechanism connected with both actuating mechanisms and under the 35 control of an operator to temporarily throw the actuating mechanism for the main feed pump out of action and simultaneously throw the actuating mechanism for the reversing pump temporarily into action.

40 A practical embodiment of the invention is represented in the accompanying drawings forming a part of this specification, in which similar characters of reference indicate corresponding parts in all the views.

45 Figure 1 is a side elevation of the actuating mechanism as applied to a two-cylinder internal combustion engine, parts being shown in section and parts being shown broken out;

50 Fig. 2 is a cross section of the same on the line 2—2 of Fig. 1;

Fig. 3 is a sectional plan view of the same on the line 3—3 of Fig. 1;

55 Fig. 4 is an enlarged sectional plan view of a portion of the reversing mechanism for the

reversing pump, the section being on the line 4—4 of Fig. 3;

Fig. 5 is a sectional side elevation of the same;

Fig. 6 is a similar view of the same on the line 6—6 of Fig. 3 and with the parts in different position; and

Fig. 7 is a sectional side elevation of the clutch mechanism connecting the eccentric of the reversing pump with its driving shaft, 65 the section being on the line 7—7 of Fig. 3.

The actuating and reversing mechanism, as shown in the drawings, is designed for a two-cylinder internal combustion engine, and for this purpose use is made of two pumps 10 and 11, one for each cylinder, to pump liquid fuel periodically into the cylinders with a view to effect explosions for normal running of the engine. The pumps 10 and 11 are mounted on a bracket 12 attached to the 70 engine frame 13, and the pumps are provided with spring-pressed plungers 14 and 15 for pumping liquid fuel into the working chambers of the cylinders. The lower outer ends of the plungers 14 and 15 are adapted to be 75 alternately engaged by arms 16 and 17 for imparting an upward movement to the plungers against the tensions of the springs there-of to force the liquid fuel into the engine cylinders. The arms 16 and 17 are pivoted 80 at 18 and 19 on the free ends of a two-armed lever 20 mounted to swing on a stud 21 attached to a bracket 22 secured to the engine frame 13, as plainly shown in Fig. 2. One arm of the lever 20 is provided with a guide-way 22 in which is mounted to slide a block 23 pivotally connected with an eccentric rod 24 of an eccentric 25 mounted on the main shaft 26 of the engine so that when the latter is running a continuous rocking motion 85 is given to the lever 20 which by the arms 16 and 17 alternately actuate the plungers 14 and 15 to pump the liquid fuel into the engine cylinders.

90 The amount of liquid pumped by the pumps 10 and 11 into the cylinder can be regulated by varying the throw given to the lever 20 and consequently varying the throw given to the plunger 14 and 15. For the purpose mentioned, the eccentric rod 24 is pivotally 95 connected with an eccentric rod 30 of an eccentric 31 having its shaft 32 journaled on the engine frame 13, and the eccentric 31 is provided with a suitable handle 33 under the control of the operator for varying the po-

100

105

110

sition of the eccentric 31 with a view to vary the position of the eccentric rod 24 and consequently that of the block 23 for moving the latter nearer to or farther from the pivot 21 thus varying the throw of the lever 20 correspondingly without change in the eccentric 25. It is understood that when the block 23 is moved nearer the pivot 21 the throw of the plungers 14 and 15 is reduced and consequently less fuel is pumped into the engine cylinders, and when the block 23 is moved farther away from the pivot 21 then the throw of the plungers 14 and 15 is increased to increase the amount of liquid fuel pumped into the cylinders.

In order to hold the arms 16 and 17 in axial alinement with the plungers 14 and 15 during the time of pushing the plungers upward, the following arrangement is made: 20 The arms 16 and 17 are pivotally connected by links 40 and 41 with a pivot 42 mounted or formed on a crosshead 43 adapted to slide up and down in a guideway 44 attached to or forming part of the bracket 22. 25 The crosshead 43 rests on a cam 50 secured to the forward end of a shaft 51 journaled in suitable bearings arranged on the bracket 22. The cam 50 is provided with a handle 52 under the control of an operator for moving 30 the crosshead 43 from its normal lowermost position into an upward position whenever it is desired to reverse the engine, as more fully explained. The handle 52 is provided with a short arm 53 pivotally connected by 35 a link 54 with the handle 55 of a cam 56 secured on a pivot 57 journaled on one end of a cylinder 58 of a horizontally disposed auxiliary reversing pump 60 mounted on the bracket 12. The reversing pump 60 is provided with a plunger 61 adapted to pump 40 liquid fuel in one of the cylinders at the time the piston thereof is in a lowermost position to effect an explosion in the said cylinder for reversing the engine, as hereinafter more 45 fully explained. The plunger 61 is provided with a head 62 adapted to be engaged by a slidable member 63 extending diametrically in the pivot 57, as plainly indicated in Fig. 5.

The outer end of the slidable member 63 50 is adapted to be engaged by the free end 64 of an arm 65 fulcrumed at 66 on a slide 67 mounted to reciprocate on a horizontal bearing 68 forming part of the bracket 12. The pivot 66 of the slide 67 is engaged by an eccentric rod 70 of an eccentric 71 mounted to turn loosely on a shaft 72 journaled in suitable bearings on the engine frame 13. The eccentric 71 is provided with a clutch member 73 adapted to be engaged by a clutch member 74 formed on a sprocket wheel 75 secured on the shaft 72. The sprocket wheel 75 is connected by a sprocket chain 76 with a sprocket 77 on the engine shaft 26 so that when the engine is running a rotary motion 60 is given to the sprocket wheel 75 which by

the clutch members 74, 73 rotates the eccentric 75 to impart a reciprocating motion to the slide 67. The arm 65 reciprocating with the slide 67 is provided near its free end 64 with a collar 80 resting on a support 81 attached to the bracket 12 and having a drop portion 82. Normally the free outer end of the slidable member 63 is out of the path of the free end 64 of the arm 65 and hence the pump 60 is not actuated during the normal 70 running of the engine although the slide 67 continually reciprocates. The top of the arm 65 is pressed on by a spring 83 to hold the collar 80 in contact with the support 81, and the said spring 83 is attached to a collar 84 held on a rod 85 erected on the base of the slide 67 to move with the latter. The collar 84 rests on a spring 86 coiled on the rod 85, and a nut 87 screws on the upper end of the rod 85 to move the collar 84 downward whenever it is desired to increase the tension of the spring 83 on the arm 65.

The cam 56 previously mentioned is provided with a nose 90 adapted to be engaged by a crosspiece 91 pivoted at 92 on the head 93 of the plunger 61, and the said crosspiece 91 is pressed on by a spring 93, and a similar spring 94 presses on a fixed crosspiece 95 permanently attached to the head 62 of the plunger 61. The springs 93 and 94 normally hold the plunger 61 in outward position relative to its cylinder 60. Normally the pivoted cross piece 91 engages the nose 90, as shown in Figs. 1 and 6, but when an upward swinging movement is given to the handle 55 on raising the crosshead 43 by the operator actuating the handle 52 then the crosspiece 91 snaps over the nose 90 to hold the pivot 57 temporarily locked against return movement. It is understood that the 100 swinging movement of the crosspiece 91 to the right is limited by a shoulder 96 formed on the head 62 at the time the crosspiece 91 reaches a right-angled position relative to the axis of the plunger 61 (see Fig. 4).

The crosshead 43 is provided on the top with an upwardly extending screw rod 100, on which screws a nut 101 forming a seat for the lower end of a spring 102 abutting with its upper end against the bracket 12. The 115 tension of the spring 102 can be regulated by correspondingly screwing the nut 101 up or down on the screw rod 100. By the use of the spring 102 the crosshead 43 is at all times held in contact with the peripheral face of the cam 50. To the crosshead 44 is attached a downwardly extending rod 110 pivotally connected with a shifting lever 111 fulcrumed at 112 on the engine frame, and the said shifting lever 101 engages the shifting 120 collar 113 of a governor 114 of any approved construction and having its shaft 115 driven from the engine shaft or other rotatable part of the engine. In case the speed of the engine increases beyond a normal rate of speed 125 130

then the governor 114 causes a lifting of the crosshead 43 whereby an outward swinging movement is given to the arms 16 and 17 by the links 40 and 41 so that the said arms 5 move out of the path of the plungers 14 and 15 to miss the same and stop feeding of liquid fuel to the engine cylinders until the speed of the engine is reduced to normal speed, at which time the crosshead 43 is returned 10 to normal lowermost position by the action of the governor 114. It will be noticed that by adjusting the nut 101 the action of the governor can be regulated when the engine is running to set the engine for 15 a predetermined speed.

The operation is as follows:

When the several parts are in the position shown in Figs. 1, 2 and 3, then liquid fuel is pumped alternately into the engine cylinders 20 by the action of the pumps 10 and 11 to periodically effect explosions for the running of the engine. When it is desired to reverse the engine, it is only necessary for the operator to swing the handle 52 downward 25 and then release it. The downward movement of the handle 52 causes the cam 50 to move the crosshead 43 upward, and in doing so the links 40 and 41 swing the arms 16 and 17 outward out of the path of the 30 plungers 14 and 15 to stop the action of the pumps 10 and 11. The downward swinging of the handle 52 causes an upward movement of the link 54 and a corresponding upward swinging movement of the handle 55 whereby 35 the pivot 57 is turned and the slideable member 63 is moved into the path of the free end 64 of the arm 65 reciprocating with the slide 67. During the movement from the right to the left given to the slideable member 63 the plunger 61 is pushed in a like direction and consequently liquid fuel is pumped into the cylinder with which the pump 10 is connected at the time. This action takes place at the time the 40 piston in the cylinder is in a lowermost position and consequently an explosion is effected to reverse the engine. During the upward swinging movement of the handle 55 the nose 90 of the cam 56 45 swings downward under the spring-pressed crosspiece 91 so that the latter swings onto the top of the nose 90 and thus temporarily locks the cam 56 and its handle 55 in an uppermost position. When the plunger 61 is pushed to the left the crosspiece 91 moves 50 with it and finally moves out of engagement with the nose 90 thus raising the cam 56 after the plunger 61 has pumped the liquid fuel into the cylinder. As soon as the handle 52 is released the spring 102 forces the crosshead 43 downward whereby the latter acts on the cam 50 and turns the latter back to normal position as shown in Fig. 1. This return movement of the cam 50 and its shaft 55 causes a downward movement of the link

54 whereby a downward swinging movement is given to the arm 55 and consequently the pivot 57 is turned and the slideable member 63 is moved out of the path of the free end 64 of the arm 65. When the plunger 61 is returned by the action of the springs 93 and 94 the crosspiece 91 abuts against the nose 90 and the cam 56 remains unlocked.

From the foregoing it will be seen that the pumps 10 and 11 are actuated regularly unless the speed of the engine increases beyond a normal rate of speed, and the pumps 10 and 11 are also rendered inactive when the handle 52 is swung downward for reversing purposes, at which time the pump 60 is put in action for forcing one charge into the corresponding cylinder at the time the piston thereof is in lowermost position or after the piston has covered or closed the exhaust. By the use of the clutch members 73 and 74 the pump 60 is actuated at the proper time.

Having thus described my invention, I claim as new and desire to secure by Letters Patent:

1. A reversing mechanism for an internal combustion engine, comprising a main feed pump adapted to supply the engine cylinder with liquid fuel to periodically effect explosions during normal running of the engine, a reversing pump adapted to supply the said engine cylinder with fuel to effect an explosion for reversing the engine, independent actuating mechanisms driven from rotatable parts of the engine, one for actuating the said main feed pump and the other the said reversing pump, connecting mechanism connected with both actuating mechanisms and under the control of an operator to temporarily throw the actuating mechanism for the main feed pump out of action and simultaneously throwing the actuating mechanism for the reversing pump temporarily into action, and means connected with the said connecting mechanism to return the actuating mechanisms to normal running position after a single pumping action of the reversing pump.

2. A reversing mechanism for an internal combustion engine, comprising a main feed pump having a spring-pressed plunger and adapted to supply the engine with liquid fuel to periodically effect the explosions in the engine cylinder during normal running of the engine, a reversing pump having a spring-pressed plunger and adapted to supply the said engine cylinder with fuel to effect a single explosion for reversing the engine, a rocking lever actuated from a movable part of the engine, an arm pivoted on the said lever and adapted to actuate the plunger of the said main feed pump, a crosshead, a link connecting the crosshead with the said lever arm, a cam lever con-

trolling the said crosshead, an actuating mechanism for the plunger of the said reversing pump, and a connection connected with the said cam lever and adapted to connect the said plunger of the reversing pump with its actuating mechanism to throw the latter into action at the time the main feed pump is thrown out of action.

3. A reversing mechanism for an internal combustion engine, comprising a main feed pump having a spring-pressed plunger and adapted to supply the engine with liquid fuel to periodically effect the explosions in the engine cylinder during normal running of the engine, a reversing pump having a spring-pressed plunger and adapted to supply the said engine cylinder with fuel to effect a single explosion for reversing the engine, a rocking lever actuated from a movable part of the engine, an arm pivoted on the said lever and adapted to actuate the plunger of the said engine feed pump, a crosshead, a link connecting the crosshead with the said lever arm, a cam lever controlling the said crosshead, an actuating mechanism driven from a movable part of the engine, and connecting means connected with the said cam lever and adapted to connect the said actuating mechanism with the plunger of the said reversing pump.

4. A reversing mechanism for an internal combustion engine, comprising a main feed pump having a spring-pressed plunger and adapted to supply the engine with liquid fuel to periodically effect the explosions in the engine cylinder during normal running of the engine, a reversing pump having a spring-pressed plunger and adapted to supply the said engine cylinder with fuel to effect a single explosion for reversing the engine, a rocking lever actuated from a movable part of the engine, an arm pivoted on the said lever and adapted to actuate the plunger of the said main feed pump, a crosshead, a link connecting the crosshead with the said lever arm, a cam lever controlling the said cross head, a slide reciprocated from a movable part of the engine, an arm pivoted on the said slide and adapted to engage the said plunger of the reversing pump, a cam lever engaging the said plunger of the reversing pump to hold the said plunger normally out of reach of the said slide arm, and a link connecting the said cam levers with each other.

5. A reversing mechanism for internal combustion engines provided with an auxiliary reversing pump having a plunger, a pivot mounted to turn and provided with

a slideable member adapted to engage the said plunger, a reciprocating slide having an arm adapted to engage the said slideable member, and means for rocking the said pivot to move the slideable member thereof into or out of the path of said slide arm. 65

6. A reversing mechanism for internal combustion engines provided with an auxiliary reversing pump having a plunger, a pivot mounted to turn and provided with a slideable member adapted to engage the said plunger, a reciprocating slide having an arm adapted to engage the said slideable member, a cam lever attached to the said pivot for turning the latter to move the said slideable member into or out of the path of the said slide arm, and a spring-pressed cross-piece pivoted on the said plunger and engaging the said cam lever. 75

7. A reversing mechanism for internal combustion engines provided with a main feed pump having a spring-pressed plunger, a rocking lever provided with a pivoted arm adapted to engage the outer end of the said plunger, a crosshead having movement in a plane approximately parallel to the axis of the plunger, a governor driven by the engine and connected with the said crosshead, and a link pivotally connecting the said crosshead with the said arm. 85

8. A reversing engine for an internal combustion engine provided with a main feed pump having a spring-pressed plunger, a rocking lever provided with a pivoted arm adapted to engage the outer end of the said plunger, a link pivoted at one end and pivotally connected at the other end with the said arm to hold the latter in axial alignment with the said plunger on reciprocating the said rocking lever, a block slideable on the said rocking lever, an eccentric on the engine shaft and having its rod connected with the said block, and a manually controlled eccentric having its rod pivotally connected with the eccentric rod of the other eccentric. 95 100

9. A reversing mechanism for internal combustion engines provided with a main feed pump having a spring-pressed plunger, a rocking lever provided with a pivoted arm adapted to engage the outer end of the said plunger, a crosshead, a governor driven by the engine and connected with the said crosshead, a link pivotally connecting the said crosshead with the said arm, a spring pressing the said crosshead, and means for adjusting the tension of the spring to adjust the said governor. 110 115

JOHANNES P. ULDERUP.
